UNITED STATES PATENT OFFICE.

JOAH BROGDEN, OF MELROSE PARK, PENNSYLVANIA, ASSIGNOR TO DAVID LUPTON'S SONS COMPANY, OF PHILADELPHIA, PENNSYLVANIA, A CORPORATION OF PENNSYLVANIA.

CABINET.

REISSUED

Application filed December 28, 1926. Serial No. 157,444.

This invention relates to cabinets of a type more particularly useful as work benches for knitters and other textile artisans.

In this connection, I aim to provide a structure which is compact, sanitary and vermin-proof, sturdy and durable, conducive to expeditious and economical manufacture from sheet metal, and serviceable as a work bench and also as a cabinet for accommodation of tools, personal belongings etc., necessary to the knitters, as well as for storage and preparation of materials to be worked by them.

Other objects and associated advantages of my invention will be manifest from the detailed description hereinafter of the typical embodiment delineated in the accompanying drawings, whereof Fig. I shows a perspective view of the cabinet.

Fig. II is a staggered plan sectional view 20 of the same, taken in accordance with the arrows II-II in Fig. I.

Fig. III is a transverse section through the structure, as designated by the arrows III-III in Fig. I.

Fig. IV is a fragmentary detail plan section 25 taken locally, as indicated by the arrows IV-IV in Fig. I.

Fig. V is a partial longitudinal section, in accordance with the arrows V-V in Fig. 30 III.

Fig. VI is a fragmentary view showing certain details at the upper rear corners of the cabinet; and,

Fig. VII is a fragmentary perspective view 35 of one of the end walls of the cabinet.

As typified in these illustrations, the cabinet is rectangular in form, comparatively long and narrow, and constructed entirely from sheet material with end walls 10 which 40 are continuous with the back 11, a top 12 and a bottom 13, the latter being preferably located at a slight elevation from the floor. The space bounded by these parts is subdivided by horizontal and vertical partitions 14, 45 15, and 16, 17 in such a manner as to afford an upper compartment 18 that extends the full length of the structure, a pair of horizontally-contiguous intermediate compartments 19, 19, and a pair of similarly-disposed 50 lower compartments 20, 20. The upper compartment 18 is preferably left open for ease of access from the front of the structure and may be utilized for storage of finished manufactures, such as stockings for example,

tools, accessories, and personal belongings 55 necessary or useful to a knitter. The intermediate compartments 19, 19 are likewise left open, and are intended for storage of packages or cones C (Fig. III) of cotton or other yarn that does not require conditioning as a pre-requisite to ready working in knitting or other textile machines. The two lower compartments 20, 20 are provided with swinging doors 21, 21, and, in order to serve in the capacity of humidors for storage 60 and conditioning of packets S of silk, rayon, etc., such materials being rendered more pliable by application of moisture, are furnished with false bottoms in the form of individually removable water pans 22 which are 65 comparatively shallow in depth and covered by perforated lids 23.

At the back, the cabinet is equipped with a horizontally-projecting hanger rail 24 useful in temporarily supporting the finished 75 stockings or other work. In the present instance, this hanger rail 24 is fashioned from a single length of channel stock with its opposite extremities laterally bent to fit against the side edges of the cabinet top 12 whereto 80 they are secured by fastening means such as screws 25. If desired, the cabinet may be further equipped with auxiliary work holders such as shown at 26, these being in the form of short arms which are appropriately 85 secured so as to project diagonally from the upper rear corners of the structure, as shown in Figs. I and VI. It is to be particularly noted that the top 12 of the cabinet is of ample area for use as a work table, and along 90 its front edge has a flush rule or scale 27 which is suitably graduated for measuring purposes.

As shown in Fig. II, the end walls 10 and the back 11 of the structure are fashioned 95 from a blank of sheet metal, which may be either in one piece or formed into one from several sections, whereof the lower edge is turned laterally inward as at 30, 30 (Figs. I and III) to provide a continuous perimeter 100 foot flange. The vertical edges of the blank are bent toward each other as at 31, Fig. II, then rearward as at 32 then outward as at 33, except within the limits of the lower compartments 20 where the terminal bends 105 are made inward to form a flange 34. The tubular frontal columns 35 thus provided not only lend strength and rigidity to the

end walls 10, but enhance the attractiveness of the cabinet as will be apparent from Fig. I. At 36, 37 and 38, Figs. I and VII, the columns 35 are cut away or notched to receive and support the front ends of the horizontal partitions 14, 15 and the bottom 13.

The bottom 13 and partition 14 are identical in size and construction: i. e., each is struck from a rectangular blank of sheet metal with down-turned securing flanges 39 along the side and rear edges, which may be screwed or welded to the end walls 10 and the back 11 of the cabinet, and finished off along the frontal edge by double bending as at 40 for stiffening and to simulate thickness at that region.

The intermediate horizontal partition 15 is similar to the parts 13, 14 except as to the treatment of its frontal edge which is given 20 an additional bend downward with provision of a flange 41 (Fig. III) for alignment with the flanges 34 of the end walls 10.

The top 12 is made after the manner of a lid with a downward perimetric flange 42 to 25 lap the end and back walls 10, 11 of the cabinet. The frontal portion of the top 12 is recessed as at 43 to take the measuring rule or scale 27 hereinbefore referred to, and terminates in a double bend 44 like that of the 30 partition 14, with appropriate cut-outs at the ends to clear the columns 35.

The vertical partition 16 between the upper compartments 19, 19 is flanged as at 45 at the top, bottom and rear for attachment to the 35 contiguous cabinet parts; and its front end 46 is double bent to hollow columnar formation and engaged in a central cut out in the frontal molding 40 of the horizontal partition 14, see Figs. IV and V.

40 The vertical partition 17 between the lower compartments 20, 20, is made in two component sections 47, 48, Figs. II and V, the first or major section being provided—like the partition 16—with a flange 49 that extends continuously along its top, rear and bottom edges; while at the front, it is bent laterally as at 50, then rearward at 51 and again laterally at 52, the latter bend registering with the terminal bends 41 and 34 of the 45 column 35 at the left and the horizontal partition 15, respectively. The section 48 of the vertical partition 17 is similarly finished at the front through a triple bend designated by corresponding reference numerals with resultant provision of continuous stop flanges for the doors 21, said doors being equipped with radial latches 53 which are operable by 50 handles 54, and adapted to engage the stop flanges aforesaid in the manner shown in Fig. II.

55 It is of course to be understood that the cabinet of my invention is not necessarily confined to the arrangement and proportions herein shown and described. In other words, 60 it may, obviously, be expanded either hori-

zontally or vertically, or both, when additional storage space and humidifying compartments are required.

Having thus described my invention, I claim:

70 1. A cabinet of the type described, composed entirely of sheet metal embodying a back and continuous end walls with the lower edge laterally turned inwards to form a continuous perimetric foot and the vertical front edges fashioned to rectangular tubulate cross-section with vertically spaced notches; a top having a perimetric flange lapping the end and back walls with the frontal edge double-channeled to provide a recess for a flush measuring rule at the front edge thereof; a bottom with down-turned securing flanges along the sides and rear edges located at an elevation above floor level and finished-off along the frontal edge by double beading; 80 and similarly sectioned horizontal and vertical partitions subdividing the cabinet into a multiplicity of separate open and closable compartments, and said closable compartments including individual false bottoms with perforate lids, for the purposes specified.

2. A cabinet of the type described, composed entirely of sheet metal embodying a back and continuous end walls with the lower edge laterally turned inwards to form a continuous perimetric foot and the vertical front 90 edges fashioned to rectangular tubulate cross-section with vertically spaced notches; a top having a perimetric flange lapping the end and back walls with the frontal edge double-channeled to provide a recess for a flush measuring rule at the front edge thereof; a bottom with down-turned securing flanges along the sides and rear edges located at an elevation above floor level and finished-off 95 with perforate lids, for the purposes specified.

100 3. A cabinet of the type described, composed entirely of sheet metal embodying a back and continuous end walls with the lower edge laterally turned inwards to form a continuous perimetric foot and the vertical front edges fashioned to rectangular tubulate cross-section with vertically spaced notches; a top having a perimetric flange lapping the end and back walls with the frontal edge double-channeled to provide a recess for a flush measuring rule at the front edge thereof; a bottom with down-turned securing flanges along the sides and rear edges located at an elevation above floor level and finished-off 105 along the frontal edge by double beading; similarly sectioned horizontal partitions supported by engagement of their forward ends in the vertical spaced notches of the columns aforesaid; vertical partitions of like character intermediate some of the horizontal partitions that afford separate open and closable compartments; and individual false bottoms with perforate lids in said closable compartments.

110 4. A cabinet of the type described, composed entirely of sheet metal embodying a back and continuous end walls with the lower edge laterally turned inwards to form a continuous perimetric foot and the vertical front 115 edges fashioned to rectangular tubulate cross-section with vertically spaced notches as well as opposed co-planar stop flanges; a top having a perimetric flange lapping the end and back walls with the frontal edge double-channeled to provide a recess for a flush measuring rule at the front edge thereof; a bottom with down-turned securing flanges along the sides and rear edges located at an elevation above floor level and finished-off 120

125

130

- along the frontal edge by double beading; similarly sectioned horizontal partitions supported by engagement of their forward ends in the vertical spaced notches of the tubulate 5 columns; vertical partitions of like character intermediate some of the horizontal partitions to afford separate open and closable compartments, one of said partitions embodying lateral stop flanges aligning with the co-planar flanges aforesaid; individual false bottoms with perforate tops in the closable compartments; and doors for said compartments seating against the stop flanges aforesaid.
- 15 4. A cabinet of the type described, composed entirely of sheet metal embodying a back and continuous end walls with the lower edge laterally turned inwards to form a continuous perimetric foot and the vertical front edges fashioned to rectangular tubulate cross-section with vertically spaced notches as well as opposed co-planar stop flanges; a top having a perimetric flange lapping the end and back walls with the frontal edge double-channelled to provide a recess for a flush measuring rule and a co-planarly disposed rail at the back edge thereof; a bottom with down-turned securing flanges along the sides and rear edges located at an elevation above floor level and finished-off along the frontal edge 45 by double beading; similarly sectioned horizontal partitions supported by engagement of their forward ends in the vertical spaced notches of the tubulate columns; vertical partitions of like profile intermediate some of the horizontal partitions to afford separate open and closable compartments, one of said partitions embodying lateral stop flanges co-planar with the stop flanges aforesaid; hinged doors for said closable compartments 50 seating on the stop flanges; individual removable humidifying pans with perforate lids in the latter compartments; and diagonal projecting bars at the upper rear angular corners 55 of the cabinet aforesaid.
- 20 5. A cabinet of the type described, composed entirely of sheet metal embodying a back and continuous end walls with the lower edge laterally turned inwards to form a continuous perimetric foot and the vertical front edges fashioned to rectangular tubulate cross-section with vertically spaced notches as well as opposed co-planar stop flanges; a top having a perimetric flange lapping the end and back walls with the frontal edge double-channelled to provide a recess for a flush measuring rule and a co-planarly disposed rail at the back edge thereof; a bottom with down-turned securing flanges along the sides and rear edges located at an elevation above floor level and finished-off along the frontal edge 60 by double beading; similarly sectioned horizontal partitions supported by engagement of their forward ends in the vertical spaced notches of the tubulate columns; vertical partitions of like profile intermediate some of the horizontal partitions to afford separate open and closable compartments, one of said partitions embodying lateral stop flanges co-planar with the stop flanges aforesaid; hinged doors for said closable compartments 65 seating on the stop flanges; individual removable humidifying pans with perforate lids in the latter compartments; and diagonal projecting bars at the upper rear angular corners 70 of the cabinet aforesaid.
- 25 6. A cabinet of the type described, composed entirely of sheet metal embodying a back and continuous end walls with the lower edge laterally turned inwards to form a continuous perimetric foot and the vertical front edges fashioned to rectangular tubulate cross-section with vertically spaced notches as well as opposed co-planar stop flanges; a top having a perimetric flange lapping the end and back walls with the frontal edge double-channelled to provide a recess for a flush measuring rule and a co-planarly disposed rail at the back edge thereof; a bottom with down-turned securing flanges along the sides and rear edges located at an elevation above floor level and finished-off along the frontal edge 75 by double beading; similarly sectioned horizontal partitions supported by engagement of their forward ends in the vertical spaced notches of the tubulate columns; vertical partitions of like profile intermediate some of the horizontal partitions to afford separate open and closable compartments, one of said partitions embodying lateral stop flanges co-planar with the stop flanges aforesaid; hinged doors for said closable compartments seating on the stop flanges; individual removable humidifying pans with perforate lids in the latter compartments; and diagonal projecting bars at the upper rear angular corners of the cabinet aforesaid.

In testimony whereof, I have hereunto signed my name at Philadelphia, Pennsylvania, this 22nd day of December, 1926.

JOAH BROGDEN.
